UNITED STATES PATENT OFFICE.

FREDERICK D. SMENNER, OF FORT WAYNE, INDIANA.

PITCH-REGULATING DEVICE FOR OCARINAS.

1,106,249.

Specification of Letters Patent.

Patented Aug. 4, 1914.

Application filed August 21, 1912. Serial No. 716,250.

To all whom it may concern:

Be it known that I, FREDERICK D. SMENNER, a citizen of the United States, residing at Fort Wayne, in the county of Allen and 5 State of Indiana, have invented new and useful Improvements in Pitch-Regulating Devices for Ocarinas, of which the following is a specification.

The invention relates to music, particularly to musical mouth instruments and has 10 for an object to provide a device for regulating the pitch of the instrument.

The invention embodies, among other features, a device particularly adaptable for use 15 in connection with mouth instruments known as ocarinas and in the use of which it is necessary to open or close a vent in order to change the pitch of the instrument. To accomplish this result use is made of an apertured casing 20 fitted over a vent of the instrument and having a member arranged to slide therein to close the openings in the casing, with means for adjusting the member in the casing in order that the vent may be increased 25 or decreased for the purpose of adjusting the pitch of the instrument in connection with the pitch of some other instrument which may be played in combination or in harmony with the ocarina.

30 In the further disclosure of the invention reference is to be had to the accompanying drawings, constituting a part of this specification, in which similar characters of reference denote corresponding parts in all the 35 views, and in which:

Figure 1 is a perspective view of the instrument; Fig. 2 is a fragmentary enlarged vertical sectional view of the pitch regulating device at one end of the instrument; 40 Fig. 3 is a vertical transverse sectional view taken on the line 3-3 in Fig. 2; and Fig. 4 is a perspective view of the member for closing the vent.

Referring more particularly to the views, 45 I disclose a body 10 constituting any well known type of musical instrument, the said body at the larger end thereof being provided with an opening constituting a vent 11, a casing 12 being mounted on the body 50 10 to inclose the vent 11, the said casing being provided with a series of elongated openings 13, as shown. Swiveled on the

casing 12 is an adjusting screw 14 having the threaded shank 15 thereof extending within the casing 12 and a member 16 has 55 threaded connection with the shank 15, the said member being sufficiently large to close the elongated openings 13 in the casing 12 when the member is screwed down by means of the adjusting screw 14. 60

It will now be readily seen that by operating the screw 14, the member 16 can be advanced or retracted in the casing 12 to cover or uncover the elongated openings 13 therein, it being also seen that the openings can 65 be partially uncovered, whereas when the member 16 is screwed down to the lowermost position in the casing 12, the opening constituting the vent 11 will be closed, it being further noted that the mentioned adjustment of the member 16 within the casing 12 provides for the regulation of the pitch of the instrument. In order to prevent the member 16 from turning or rotating 70 in the casing 12, guides 17 are struck 75 from or formed with the member 16 to extend through a plurality of the elongated openings 13 in the casing, thus preventing any rotation of the member within the casing. 80

Having thus described my invention, I claim:

1. A body of the character described having a vent-opening, an apertured casing on the body and encircling the vent-opening, 85 and means movable within the casing to cover or uncover the apertures therein.

2. A body of the character described having a vent-opening, a casing on the body and covering the vent-opening, the said casing being provided with a series of apertures, a member slideable longitudinally within the casing to cover or uncover the apertures therein, and an adjusting screw carried by the casing and having connection 90 with the member for advancing or retracting the same within the casing. 95

3. A body of the character described having a vent opening, a casing on the body and covering the vent opening, the said casing 100 being provided with a series of apertures, a member slideable longitudinally within the casing to cover or uncover the apertures therein, an adjusting screw carried by the

casing and having connection with the member for advancing or retracting the same within the casing, and means carried by the member and engaging the casing for preventing rotation of the member relatively to the casing when the said adjusting screw is actuated.

In testimony whereof I affix my signature in presence of two witnesses.

FREDERICK D. SMENNER.
